UNITED STATES PATENT OFFICE.

VIRGINIA NEAL, OF SAN FRANCISCO, CALIFORNIA.

DESIGN FOR A RADIOCABINET.

Application filed January 19, 1925. Serial No. 12,090. Term of patent 7 years.

To all whom it may concern:

Be it known that I, VIRGINIA NEAL, a citizen of the United States, residing at San Francisco, in the county of San Francisco and State of California, have invented a new, original, and ornamental Design for Radiocabinets, of which the following is a specification, reference being had to the

accompanying drawing, forming part thereof.

The figure is a perspective view of a radiocabinet, showing my new design.

I claim:

The ornamental design for a radiocabinet, as shown.

VIRGINIA NEAL.
